UNITED STATES PATENT OFFICE

GEORGE E. LEACH, OF MINNEAPOLIS, MINNESOTA, ASSIGNOR TO BROWN & BIGELOW, OF ST. PAUL, MINNESOTA, A CORPORATION OF MINNESOTA

DESIGN FOR A KNIFE

Application filed August 27, 1931. Serial No. 40,938. Term of patent 7 years.

To all whom it may concern:

Be it known that I, GEORGE E. LEACH, a citizen of the United States, residing in Minneapolis, in the county of Hennepin and State of Minnesota, have invented a new, original, and ornamental Design for a Knife, of which the following is a specification, reference being had to the accompanying drawings, forming a part thereof.

Figure 1 is a top end view of a knife in a closed position showing my new design.

Figure 2 is a side perspective view, with the blade of the knife open.

Figure 3 is a bottom edge view of the same in a closed position.

I claim:

The ornamental design for a knife as shown.

GEORGE E. LEACH.
